UNITED STATES PATENT OFFICE.

CHARLES W. WANGER, OF RIVERTON, NEW JERSEY.

DESIGN FOR A BIB-FAUCET.

49,787.

Specification for Design.

Patented Oct. 17, 1916.

Application filed July 10, 1916. Serial No. 108,475. Term of patent 14 years.

To all whom it may concern:

Be it known that I, CHARLES W. WANGER, a citizen of the United States, and a resident of Riverton, Burlington county, New Jersey, have invented a new, original, and ornamental Design for Bib - Faucets, of which the following is a specification, reference being had to the accompanying drawing, in which—

Figure 1, is a plan view, Fig. 2, is a side elevation, and Fig. 3, is a front elevation of a bib faucet embodying my design.

I claim:

The ornamental design for a bib faucet, substantially as shown in the accompanying drawing.

CHARLES W. WANGER.
